Minneapolis-Honeywell Regulator Company, Minne-
apolis, Minn., a corporation of Delaware

Application October 30, 1957, Serial No. 48,281

Term of patent 14 years

(Cl. D61—1)

FIG. 1

FIG. 2

FIG. 3

Fig. 1 is a side elevational view of a photographic flash unit, showing my new design; the opposite side being substantially a mirror image thereof;

Fig. 2 is a front elevational view; and

Fig. 3 is a rear elevational view thereof.

The dominant features of my new design are shown in solid lines in the drawing.

The broken line showing of legible matter in Fig. 3 is for illustrative purposes only.

I claim:

The ornamental design for a photographic flash unit, substantially as shown and described.
